(57) **CLAIM**

The ornamental design for a cable actuated switch operating device, substantially as shown and described.

DESCRIPTION

FIG. 1 is a perspective view of a cable actuated switch operating device according to the present invention;

FIG. 2 is a front side elevation view thereof;

FIG. 3 is a left side elevation view thereof;

FIG. 4 is a top plan view thereof;

FIG. 5 is a rear side elevation view thereof;

FIG. 6 is a right side elevation view thereof; and,

FIG. 7 is a bottom plan view thereof.

The broken line portion of the figure drawings is included to show unclaimed subject matter only and forms no part of the claimed design.

1 Claim, 3 Drawing Sheets

FIG. 1
